UNITED STATES PATENT OFFICE.

JOHN F. O'CONNOR, OF CHICAGO, ILLINOIS, ASSIGNEE TO WILLIAM H. MINER, OF CRAZY, NEW YORK.

FRICITION-GEAR FOR RAILWAY-CAR DRAFT-RIGGINGS.

1,255,213.

Specification of Letters Patent.

Patented Feb. 5, 1913.

Application filed March 18, 1913. Serial No. 13,880.

To all whom it may concern:

Be it known that I, JOHN F. O'CONNOR, a citizen of the United States, residing at Chicago, in the county of Cook and State 5 of Illinois, have invented a certain new and useful Improvement in Friction-Gears for Railway-Car Draft-Riggings, of which the following is a full, clear, concise, and exact description, reference being had to the accompanying drawings, forming a part of this specification.

This invention relates to improvements in friction gears for railway car draft riggings.

15 An object of the invention is to provide a high capacity friction gear for railway car draft riggings and one in which the release is always certain.

The invention furthermore consists in the 20 improvements in the parts and devices and in the novel combinations of the parts and devices, as herein shown, described or claimed.

In the drawing forming a part of this 25 specification, Figure 1 is a longitudinal, vertical sectional view of a draft rigging embodying my improvements and showing the parts in full release. Fig. 2 is a horizontal sectional view of the structure shown in 30 Fig. 1, the parts being illustrated in their full buff position and in this figure the section through the friction shoes, wedging means and anti-friction rollers is taken on planes arranged at an angle of 120 degrees. 35 Figs. 3 and 4 are vertical sectional views taken on the lines 3—3 and 4—4 respectively of Fig. 1. Fig. 5 is a detail end view of the wedge and Fig. 6 illustrates another embodiment of my improvements.

40 In said drawing and referring to Figs. 1 to 5 inclusive, 10 denotes the center sills, the same having secured thereto rear stops 11 and front stops 12. A draw-bar 13 of the usual type is provided and the same is 45 connected with the gear proper by means of a preferably cast steel yoke 14 connected to the draw-bar by a coupler key 15 which reciprocates in slots in the sills and front stop castings 12. The rear portion of the gear is 50 supported by a saddle or tie plate 16.

The friction gear proper comprises a friction shell 17 having a spring chamber at the rear end thereof in which is located a spring 18 which comprises an inner and an outer 55 coil. Said shell 17 is also provided at its

rear end with an integral rear follower 19. Mounted within the friction shell is a plurality of friction shoes 20, three in number as shown, said shoes having their outer ends normally extended beyond the end of the 60 shell (see Fig. 1). Coöperable with the shoes is a wedge 21 located within the hollow formed by the shoes, said wedge 21 acting directly against the spring 18 through the cup shaped spring follower 22. Interposed between the rear end of the draw-bar butt and the gear is a front follower 23 and between it and the friction shoes is a cup shaped thrust block 24, said block being so designed that the inwardly extending cup 70 portion 25 thereof is slidable within the outer ends of the friction shoes and the rim or annular flange 26 thereof is small enough to slide within the friction shell (see Fig. 2). Each of the friction shoes 20 is provided 75 with a roller bearing, wedging face 27 inclined inwardly toward the axis of the gear and the wedge block 21 is provided with a plurality of corresponding but oppositely inclined roller bearing wedge faces 28. A 80 plurality of anti-friction rollers 29 are mounted between said wedging faces and on their outer portions bear upon a wear plate 30 located on the inner end of the cup 25 of the thrust block 24. A retaining through 85 bolt 31 is provided to hold the parts in assembled position and also the spring under an initial compression.

The operation of the gear is as follows: Upon inward movement of the draw-bar, 90 the front follower 23 moves the thrust block 24 inwardly and this in turn through the wear plate 30 causes the anti-friction rollers 29 to ride radially and longitudinally of the gear on the inclined faces 27 of the friction 95 shoes. Such movement of the rollers in turn causes axial movement of the wedge 21 and compression of the spring 18. This movement of the block 24, plate 30, anti-friction rollers and wedge takes place while the friction shoes 20 remain stationary due to the relatively great friction between them and the friction shell. The friction shoes remain in this stationary condition until the space which is normally between the flange 105 of the block 24 and the ends of the friction shoes is taken up, whereupon the shoes will be moved inwardly simultaneously with the other parts. As this movement continues the outward thrust against the friction shoes 110

is uniformly augmented, due to the continuing compression of the spring and the final movement is limited by engagement of the front follower 23 with the end of the friction shell and the limiting stops. Upon release, the friction shoes will remain stationary during initial portions of such action and the wedge, thrust block and anti-friction rollers will be moved outwardly independently of the shoes until the flange of the spring follower 22 engages the inner ends of the friction shoes. At this time, of course, the pressure against the friction shoes has been greatly reduced and the shoes can then be readily moved outward and this occurs under the influence of the spring, the shoes, wedge, rollers and thrust block all moving simultaneously until the full release is obtained.

In the construction shown in Fig. 6 the parts are quite similar to those illustrated in the other figures of the drawing, with the exception that the friction shoes 120 have plain inner faces upon which the anti-friction rollers 129 roll. In other words, the anti-friction rollers 129 are given only a longitudinal movement during the initial action of the gear and not a combined longitudinal or axial and radial movement as in the other construction. With the arrangement shown in Fig. 6, the wedge 121 will travel linearly at the same rate as the follower 123, whereas with the construction illustrated in the other figures, the lineal speed of the wedge 21 will be somewhat greater than that of the front follower 23, due to the combined axial and radial travel of the anti-friction rollers 29. Otherwise the operation for both structures is the same both in application of the stresses and release.

I claim:

1. A friction gear for draft riggings comprising a friction shell, shoes coöperable therewith, a wedge, a spring, a thrust block, and anti-friction rollers, each roller being interposed between and engaging the wedge, shoes and thrust block.

2. A friction gear for draft riggings comprising a friction shell, friction shoes, a spring, a wedge acting directly against said spring, anti-friction means between the

wedge and friction shoes, and a thrust member normally out of engagement with said friction shoes and arranged, after an initial compression of the gear, to directly engage said shoes and transmit pressure thereto in lines parallel to the axis of the gear.

3. A friction gear for draft riggings comprising a friction shell having a spring chamber and an integral rear follower, a spring contained within said chamber, friction shoes coöperable with said shell, a wedge acting directly against said spring, a front follower, anti-friction rollers interposed between said wedge and shoes, and means for applying thrust from said follower to said anti-friction rollers in lines parallel with the axis of the gear, said friction shoes remaining stationary during initial portions of the actuation and release of the gear, said wedge, rollers, and front follower moving during said initial portions of the actuation.

4. A friction gear for draft riggings comprising a friction shell, a spring, a plurality of friction shoes within said shell, a wedge located within the shoes and acting directly against said spring, said wedge having its wedge faces at the front end thereof and the shoes having wedge faces opposite thereto and diverging therefrom, anti-friction rollers mounted between the sets of diverging wedge faces, a front follower, and a thrust member interposed between said follower and said rollers and acting directly against the latter, said thrust member extending partly within the shoes.

5. A friction gear for draft riggings comprising a friction shell, friction shoes coöperable therewith and having their outer ends extended normally beyond the end of the friction shell, a follower having a thrust block on the inner face thereof, the latter being normally spaced from the adjacent ends of the friction shoes, a wedge located within the shoes, a spring directly acted upon by said wedge at one end, and anti-friction means located in the space formed between the wedge, shoes and thrust block.

JOHN F. O'CONNOR.
